UNITED STATES PATENT OFFICE.

LOUIS ERNEST FRANCOIS FERRETTE, OF PARIS, FRANCE.

MINER'S INCANDESCENT SAFETY LAMP.

Application filed July 28, 1923, Serial No. 654,424, and in France August 12, 1922.

This invention has reference to a miner's incandescent safety lamp in which benzine, petrol or other oils may be used as the combustible, the incandescent light being produced by a mantle.

The object of the present invention is to provide improvements in the construction of a lamp of the kind referred to.

According to the present invention I provide a miner's incandescent safety lamp, wherein the burner flame and the intensity of light are regulated by controlling the supply of combustible admitted to a vapourizer and wherein the combustible vapours are filtered before being admitted to the burner, the said combustible being also subjected to the pressure caused by a pump arranged in the lamp reservoir.

Reference is now made to the annexed drawings wherein is illustrated by way of example, one form of lamp constructed in accordance with the present invention.

Referring to the drawings:—

The figure is a vertical sectional view of the lamp.

Referring to the drawing the lamp reservoir 1 is provided with a tube 2, wherein the bottom part of a valve 3 is arranged, said valve comprising a needle 4 operated by a lever 5 projecting out of the bottom of the reservoir 1. A union 6 connects the valve 3 to a tube 7 arranged within the said reservoir and provided with a gauze 8 for filtering the combustible.

The valve 3 is provided with a three connection union 9, connected with one end of a coil vapourizer 10, the other end of said vapourizer, which is also provided with a three connection joint 11, being fixed to the upper part of the gas tube 12. The latter is provided in its interior with a metallic filter 13, which can be easily removed by means of a screwed plug, 14, when the lamp is opened. The gas tube 12 is provided with a branch 15 having a nozzle holder 16 wherein is screwed a nozzle 17. The latter is fitted with a Bunsen burner 18 which is held in place by a collar 19 supported by the union 9 and the gas tube 12. A mantle 20 is arranged above the burner 18 and is supported by a rod 21, fixed in a mantle holder 22 by a screw 23.

The pressure necessary for the feeding of the combustible to the lamp burner is obtained by means of a pump provided in the reservoir 1 and comprising a body 25 in the

interior of which a piston 26, having a leather cup 27 fixed at the end of a hollow rod 28, is movably arranged.

The piston rod 28 is provided with a knob 60 24 which is uncovered by the thumb of the operator at the time of the intake of air (i. e. the outstroke of the piston) so as to allow the air to enter the pump through the rod 28, the said knob being covered by the 65 thumb on the instroke of the piston. The air compressed by the pump opens a valve 29 held against a valve seat 30 by a spiral spring 31, the stem of the valve being slidably guided in an aperture 32 formed in the 70 wall of a chamber 33 enclosing the valve and valve seat.

A safety valve, situated at the top part of the reservoir 1, comprises a seat 34 whereon is arranged a sheet lead disc 35 on the 75 edges of which rests the flange 36 of a cup 37 provided, at its central part, with a needle or piercing device 38 and held down on the disc 35 by means of a nut 39. The cup 37 is formed with a small hole 40 which allows 80 the pressure within the reservoir 1 to drop when the disc 35 is perforated by the needle 38.

Air necessary for the combustion of the fuel passes into the interior of the lamp 85 through two metallic gauze filters 41, and a guard 42, serving to protect the parts of the lamp, is secured to the lower portion of the upper part of the lamp.

When the lamp has been provided with 90 the combustible, in order to obtain the required pressure within the reservoir 1, a certain number of strokes are made with the pump piston 26, the passage in the piston rod 28 being closed on the instroke by placing the thumb over the button 24. When the vapourizer coil 10 is sufficiently heated, the lever 5 of the needle 4 is rotated so as to allow the combustible, after rising through the tube 7, to pass into the said vapourizer 100 100 coil 10 which latter may be heated in any known suitable manner.

The combustible is vapourized as it passes through the coil 10 and the vapours are led through the gas tube 12 where they are 105 filtered by the filter 13 before reaching the nozzle 17. After passing through the said nozzle, the gases flow into the burner 18, drawing the air necessary for their combustion through openings provided in the lower 110 part of the burner, and are burnt at the upper part of the burner.

The mantle is very quickly raised to incandescence, the duration of working of the lamp depending upon the amount of combustible in the reservoir 1. The intensity 5 of the light can be varied at any time by moving the needle valve 4 towards or away from its seat.

Having now particularly described and ascertained the nature of my said invention 10 and in what manner the same is to be performed, I declare that what I claim is:—

1. A miner's incandescent safety lamp, comprising a base providing a fuel reservoir, a feed tube opening into the reservoir, 15 a valve operable from beyond the reservoir and controlling the flow through the feed tube, a burner section mounted above the reservoir, a Bunsen burner supported in said section, an incandescent mantle supported 20 above the burner, a vaporizing tube coiled about the mantle and open to the supply from the feed tube, a metallic filter arranged between the vaporizing tube and Bunsen burner, and a guard section depending from 25 the burner section and open at the lower edge for the admission of air to the burner.

2. A miner's incandescent safety lamp, comprising a base providing a fuel reservoir, a feed tube opening into the reservoir, a 30 filter at the inlet end of such tube, a valve operable from beyond the reservoir and con-

trolling the flow through the feed tube, a burner section mounted above the reservoir, a supporting collar carried by the burner section, a Bunsen burner supported on said collar, an incandescent mantle supported above the burner, a vaporizing tube coiled about the mantle and open to the supply from the feed tube, said tube being supported by said collar and a metallic filter 35 arranged between the vaporizing tube and Bunsen burner.

3. A miner's incandescent safety lamp, comprising a base providing a fuel reservoir, a feed tube opening into the reservoir, a valve operable from beyond the reservoir and controlling the flow through the feed tube, a burner section mounted above the reservoir, a guard intermediate the reservoir and burner section and open to the atmosphere, a Bunsen burner supported in said section, the burner section being formed with an air opening underlying the burner, gauze filters in said opening, an incandescent mantle supported above the burner, a vaporizing tube coiled about the mantle and open to the supply from the feed tube, and a metallic filter arranged between the vaporizing tube and Bunsen burner.

In testimony whereof I affix my signature.

LOUIS ERNEST FRANÇOIS FERRETTE.
